SKI FITTING

Harvey E. Dodds, Toronto, Ontario, Canada

Application October 21, 1939, Serial No. 300,616

1 Claim. (Cl. 280—11.35)

My invention relates to ski fittings and more specifically to the harness component thereof wherein the harness comprises in combination with toe-holding irons, a heel encircling resilient cable adapted to hold the rider's shoe in the toe-irons. Generally the subject matter of this application resides in a means for tightening the cable.

One of the objects of the invention is to provide quick and effective means to tighten and release a ski harness cable.

Another object of the invention is to provide a device for tightening and releasing a ski-fitting cable in which are incorporated means to adjust the amount of pull on the cable as well as to adjust the cable to various size boots.

A further object of the invention is to provide a cable tightening and releasing device which permits self equalization of the cable snugly holding the same at all times, and easy removal of the cable therefrom when so desired.

A further object of the invention is to provide such a device which will hold the cable in a manner so as to clear the front of the shoe and which will also avoid any damage to the cable.

A still further object of the invention is to provide a harness-cable take-up device which is simple in adjustment, attractive, easily installed and comparatively economical to manufacture.

Other objects as well as many advantages of the invention will become apparent in the following description of a preferred embodiment thereof illustrated in the accompanying drawings in which:

Fig. 1 is a top plan view of the central section of a ski with which my invention is incorporated;

Fig. 2 is a side elevation of the cable take-up mechanism in its tightened aspect;

Fig. 3 is a side elevation thereof in its released aspect, for the most part in section; and,

Fig. 4 is a top view of the cable engaging portion being for the greater part a transversal section of the cable sheaf.

Similar reference numerals denote identical parts in all the figures.

Referring to Figure 1, numeral 5 indicates the central portion of a wooden ski, although my invention is applicable to any type of ski be it of the solid wood, laminated, or metal construction, while 6 represents the position of the heel of the rider. This position is of course merely for the purpose of illustration as is the location of toe iron fittings 7 which obviously vary according to the size of the boot accommodated.

The harness cable is shown at 8 possessed of its elasticity commonly provided by means of heel encircling portion 9 which is usually in the nature of a spring.

The purpose of the cable is obviously to hold the boot against irons 7 by tension applied thereto, and this tension is obtained through the front take-up comprising amongst other parts a base lug 8^a and lever 9^a. To lever 9^a is pivoted a strap 10 to which is riveted rod member 11 threaded at one end in sleeve 12. Threaded in the other end of said sleeve is a rod 13 having its end shaped in the form of a hook 14 in engagement with cable sheaf 15. While both members or rods 11 and 13 are threaded in sleeve 15 12, it will be noted that one is provided with a right hand thread 20 while the other is provided with a left hand thread 21. Accordingly, the sleeve is threaded for half its length in one direction while the remainder is threaded in the reverse direction with the result that by turning the sleeve one way or the other, rods 13 and 11 may be either brought towards each other or separated as may be desired.

Sheaf 15 comprises a U shaped member in 25 which the cable passes, it being curved longitudinally to prevent any undue strain on the cable. The sheaf is preferably fixed in the hook 14 such as by spot welding and is provided with inwardly projecting depressions 22 to offer resistance to the passing of the cable therein. This will safeguard against accidental falling of the cable when in released condition.

Lug 8^a has its base in channel form and is held to the ski by means of screws 16 passing 35 through openings therein as shown. The sides of channel extend at one end to form two parallel ears 17 having perforations to receive rivet 18 pivoting the end of lever 9^a. Strap 10 is pivoted to lever 9^a by rivet 18 so that when in the position shown in Figure 3, pivoted point 19 is above or behind pivotal point 18. When the lever is brought down, however, pivotal point 19 reaches forward of point 18 drawing the cable until the two points are on dead center or point 19 slightly below center line of 18 thereby holding lever 9^a against upward movement.

In first use, before placing the boot on the ski, lever 9^a is lifted as in Figure 3 and sleeve 12 turned in the proper direction until members 12 50 and 13 are separated as far as they may be. This will loosen cable 8^a to the fullest extent so that the boot may be fitted in the irons, 7, its heel resting within portion 9^a of the cable. Sleeve 12 is then turned until the cable is fairly close 55

to the heel and lever 9^a brought down to the position shown in Figure 2. If the cable is too tight or too loose lever 9^a is lifted again and the sleeve adjusted accordingly. For further use it is only necessary to manipulate lever 9^a when attaching or removing the ski.

While I have described my invention in strict accordance with the embodiment shown, it must be understood that changes may be made without departing from the spirit of the invention and scope of my claim.

Having regard to the foregoing disclosure, the patent of which this specification forms part confers, subject to the conditions prescribed in the Patent Act, 1935, the exclusive right, privilege and liberty of making, constructing, using and vending to others to be used, the invention as de-

fined in claim submitted by the patentee as follows:

A ski harness comprising a flexible endless cable, and take-up means for said cable, said means comprising a rock lever, means pivotally mounting said lever on the ski, a U-shaped strap pivotally secured to said lever, turnbuckle means connected at one end with the bight of said strap, a hook at the opposite end of said turnbuckle means, a sheave carried by said hook, said sheave being longitudinally curved and said cable engaging in said sheave, and a pair of detents carried by said sheave on opposite sides of said hook for holding said cable therein while permitting movement of said cable lengthwise of said sheave. 5 10 15
